Primary Examiner — Elizabeth Albert(74) *Attorney, Agent, or Firm* — Kintner IP, LLC; Mary Frances Ludwig(57) **CLAIM**

The ornamental design for a seed propagation frame, as shown and described.

DESCRIPTION

FIG. 1 is a front perspective view of a seed propagation frame showing my new design;

FIG. 2 is a rear perspective view thereof;

FIG. 3 is a top plan view thereof;

FIG. 4 is a left side elevation view thereof, the right side elevation view being a mirror image;

FIG. 5 is a bottom plan view thereof; and,

FIG. 6 is a reduced scale front perspective view of the design of FIG. 1 in use.

The long and short broken lines represent the bounds of the claimed design and form no part thereof; the evenly spaced broken lines show portions that form no part of the claimed design.

My seed propagation frame is intended to support a seed partially submerged in water for purposes of propagation.
